Fig. 1 Peter Par Design for Cooking Stove Patented May 22nd 1847.

Des. 123

Peter Low. Troy. New York.

Letters Patent Design No. 123. dated 22nd May 1847.

The schedule referred to in these Letters Patent and making part of the same.

To all whom it may concern: Be it known that I, Peter Low, of the City of Troy, County of Rensselaer and State of New York have invented or produced a new Cooking Stone Pattern; the Stones made from which are to be called the American Hot Air Cooking Stove; and do hereby declare that the drawing or cut-marked Fig. 1 accompanying this specification and the cast Plates marked Fig. 1. Fig. 2. Fig. 3. Fig. 4. Fig. 5. Fig. 6. and Fig. 7. sent as a model of said Pattern are a full and exact description of the same.

What I claim as new and desire to secure by Letters Patent is the production of the new patterns above described.
